UNITED STATES PATENT OFFICE.

WILLIAM N. FOX, OF SAN ANTONIO, TEXAS.

DISPLAY OR ADVERTISING DEVICE.

1,266,446.

Specification of Letters Patent. Patented May 14, 1918.

Application filed February 16, 1918. Serial No. 217,602.

To all whom it may concern:

Be it known that I, WILLIAM N. Fox, a citizen of the United States, residing at San Antonio, in the county of Bexar and State 5 of Texas, have invented new and useful Improvements in Display or Advertising Devices, of which the following is a specification.

This invention relates to display or advertising devices and it consists in the novel 10 features hereinafter described and claimed.

An object of the invention is to provide a device of the character stated which is of simple and durable structure and which may 15 be easily and conveniently used for displaying or exposing an advertising sign in a manner to attract attention to the same and thereby enhance the value of the device for advertising or display purposes.

20 With this object in view the device comprises a barrel which may be in the form of a bottle, cannon or other similar article and which if desired may be mounted in trunnion bearings.

25 Arms are pivotally mounted at the mouth of the barrel and rods are slidably mounted in the said arms and pivotally connected at their inner ends with a block or similar member mounted for movement in the barrel. 30 The advertising sign is carried by the said rods. A cylinder is located in the barrel and means are provided for introducing air under pressure, alternately in the opposite ends of the said cylinder. A piston is 35 mounted for sliding movement in the cylinder and a rod operatively connects the piston with the block. The parts are so connected together that when air is introduced into the cylinder the piston is moved therein and the 40 rods may be projected beyond the end of the barrel and spread so that the sign which is carried by the rods is stretched and the legends which appear thereon are visible. On the other hand when the air is introduced into 45 the cylinder to move the piston in an inward direction the rods are withdrawn within the barrel and the sign is carried into the barrel by the rods and consequently it is concealed.

50 In the accompanying drawings:—

Figure 1 is a longitudinal sectional view of the display or advertising device.

Fig. 2 is a fragmentary similar view of the same showing the sign in extended position.

Fig. 3 is a front view of the sign which

may be used in conjunction with the device and

Fig. 4 is a fragmentary sectional view of the valves for controlling the admission and 60 exhaust of the air under pressure to the cylinder.

As illustrated in the accompanying drawings, the barrel 1 is in the form of a bottle, but it is to be understood that the said barrel 65 may be in the form of any other article as for instance a gun or cannon. The barrel 1 is provided at its sides with trunnions 2 which may be pivoted in suitable trunnion bearings (not shown). The barrel 1 is provided at its mouth with longitudinally disposed slots 3 in which arms 4 are pivotally mounted. Rods 5 are slidably mounted in the arms 4 and the said rods at their inner ends are pivotally connected with a block 6 70 75 which is slidably mounted in the barrel 1. A sign 7 is connected at its corner portions with the outer ends of the rods 5 and the said sign may bear upon its adverse surface or face any suitable advertising characters 80 or legends.

A cylinder 8 is located at the inner end portion of the barrel 1 and a piston 9 indicated by dotted lines in Fig. 1 is slidably mounted in the cylinder 8. A rod 10 operatively connects the piston 9 with the block 6. Pipes 11 and 12 connect with the opposite end portions of the cylinder 8 beyond the opposite sides of the piston 9 and each of the said pipes is provided with a valve 13. In 85 view of the fact that the said valves are of the same structural arrangement a description of one will suffice. The casing of each valve 13 is provided with an exhaust port 14 and the casings of the valves 13 connect with nipples 15 which in turn connect with a pipe 16 through which air may be produced into the casings of the valves 13. A valve member 17 is turnably mounted in the casing of each of the valves 13 and each member 17 90 95 is provided with a passageway 18 which may be moved into register with the exhaust port 14 and either of the pipes which is connected with the cylinder 8 or may be moved to a position whereby the nipple 15 is connected with either of the pipes which is connected with the cylinder 8. Handles 19 are connected with the stems of the valve members 17 and a bar 20 is pivotally connected at its ends with the free end portions of the 100 105 handles 19.

Assuming that the parts of the device are

in the positions as shown in Fig. 1 of the drawing, and it is desired to extend the sign with relation to the barrel 1 an operator grasps the bar 20 and moves the same 5 longitudinally whereby the passageway 18 is moved into register with the pipe 11 and the adjacent nipple 15. At the same time the member 17 in the other casing 13 is moved so that its passageway is brought 10 into register with the pipe 12 and the exhaust port 14. Thus it will be seen that the air may enter the pipe 11 through that valve casing 13 which is connected with the same and at the same time the air from 15 the forward portion of the cylinder 8 is exhausted therefrom through the pipe 12. Consequently the piston 9 is moved along the cylinder 8 and the block 6 is moved in a forward direction whereby the rods 5 are 20 projected beyond the mouth of the barrel 1 and the sign 7 is stretched and the characters or legends which are upon the sign become visible. Should it be desired to withdraw the sign and the arms to 25 position within the barrel 1, the bar 20 is manipulated whereby the air is permitted to flow from the pipe 16 through the pipe 12 into the forward end of the cylinder 8 and at the same time the 30 air at the rear end of the cylinder 8 is exhausted through the pipe 11 and the valve casing which is connected with the said pipe. Thus the rods and the sign are moved from an exposed position beyond 35 the end of the barrel to a concealed position within the barrel.

From the foregoing description taken in conjunction with the accompanying drawings, it will be seen that a display or advertising device of simple and durable structure is provided and that the same may be easily and quickly manipulated to project a sign beyond a barrel or body and withdraw the same within the barrel or 45 body.

Having described the invention what is claimed is:—

1. A device of the character stated comprising a body, arms pivoted at the mouth 50 of the body, rods slidably mounted in the arms, and a sign carried by the rods and means for moving the rods through the arms.

2. A device of the character stated comprising a body, arms pivoted at the end of 55 the body, rods slidably mounted in the arms,

a sign carried by the rods, a block connected to the rods and slidably mounted in the body, pneumatic means for moving the block.

60

3. A device of the character stated comprising a body, arms pivoted at the end of the body, rods slidably mounted in the arms, a sign carried by the rods, a block connected to the rods and movably mounted in the body, a cylinder located in the body, a piston slidably mounted in the cylinder, means for operatively connecting the piston with the block and means for introducing air under pressure at the opposite ends of the cylinder.

70

4. A device of the character stated comprising a body, rods slidably mounted at the end of the body, a sign carried by the rods, a block slidably mounted in the body and pivotally connected with the rods, a cylinder located in the body, a piston slidably mounted in the body and operatively connected with the block and means for introducing air under pressure at the opposite ends of the cylinder.

80

5. A device of the character stated, comprising a body, a sign within the body and collapsed therein, means for projecting the sign from the body, and means arranged at the mouth of the body for spreading the sign as it leaves the body.

85

6. A device of the character stated, comprising a body, a sign within the body and collapsed therein, means for projecting the sign from the body, and means arranged at the mouth of the body for spreading the sign as it leaves the body, said last means including elements engaged with the sign in such manner as to open the sign at right angles to its axis.

95

7. A device of the character stated, comprising a body, a sign within the body and collapsed therein, means for projecting the sign from the body, and means arranged at the mouth of the body for spreading the sign as it leaves the body, said last means including elements engaged with the sign in such manner as to open the sign to a substantially flat condition.

100

8. A device of the character stated comprising a body, spreading means at the mouth of said body, rods slidably mounted in the spreading means, and a sign carried by the rods and means for moving the rods through the spreading means.

110

In testimony whereof I affix my signature.

WILLIAM N. FOX.
